FIG. 8.

UNITED STATES PATENT OFFICE.

YOBIE NAKANISHI, OF LOS ANGELES, CALIFORNIA.

GARMENT PRESS.

Application filed June 19, 1922. Serial No. 569,398.

To all whom it may concern:

Be it known that I, YOBIE NAKANISHI, a subject of the Emperor of Japan, residing in the city and county of Los Angeles 5 and State of California, have invented a new and useful Garment Press, of which the following is a specification.

This invention relates to improvements in garment presses, and its objects are to 10 provide a device of this kind embodying means for easy, rapid, convenient and successful pressing of garments, together with an economical operating expense therefor.

Other objects of this invention consist of 15 providing a garment press having a maximum of clearance for the operator, flexibility of adjustment to the varying thickness of the material to be ironed or pressed, and means for applying heat to the garment.

With the improved construction embodied in the present invention, I am enabled to smooth and iron out the wrinkles and creases in the garments with great facility, and this 25 I accomplish by the simple and inexpensive device, substantially as hereinafter more fully described and pointed out in the claims.

In the drawings:

30 Figure 1 is a perspective view of my improved garment-presser device. Fig. 2 is a detail and bottom plan view of the ironing-head with the ironing plate removed. Fig. 3 is a fragmentary and sectional detail 35 view of the ironing head. Fig. 4 is a side elevation of the garment-pressing device, with a part thereof in section to show the means for operating the pressing buck. Fig. 5 is a longitudinal and horizontal section 40 view of the pressing buck. Fig. 6 is a longitudinal and vertical sectional view of the pressing buck. Fig. 7 is a diagram of the electric wiring and heating elements. Fig. 8 is a fragmentary and sectional detail 45 view of the supporting yoke.

Referring more particularly to the drawings, my improved garment-press consists of a standard 21, a yoke 22 integral therewith, and a table 23 supported by legs 24 and the 50 standard. The ironing head 25 is integral with movable arm 26, pivotally connected with movable arm 27, which is pivotally mounted on the cylindrical portion 28, of yoke 22, and supported by collar 29 and bearing cap 30, the collar being screw-

threaded to engage with the threaded portion 71 for adjustment, and retained in adjusted position by set-screw 31. The ironing head consists of movable arm 26, integral casing 32 and integral operating handle 33. 60

Within casing 32, and projecting at the bottom thereof, is a revolvably mounted ironing plate 34, connected by arms 35, to a rotative shaft 36, which has an integral contact head 37 having contact rings 38 and 39. Fig. 2 shows a bottom view of the ironing member with the plate 34 removed from the heating element 46, which is carried by arms 35. Spring-pressed contact brushes 40, in engagement with rings 38 and 39, and mounted in a fixed insulating block 41, are connected to circuit terminals 42 and 43. In Fig. 3, of the drawings, a portion of shaft 36 is shown in elevation to illustrate the cylindrical surface thereof. 75 Contact rings 38 and 39, are connected by insulated wire conductors 44 and 45, to heating elements 46, which, when energized, will heat ironing plate 34. An electric switch 47, mounted on standard 21, serves to control the circuit for energizing the heating elements 46.

Means for rotating plate 34, consist of a motor 48, controlled by a switch 49 mounted on handle 33, through pinion 50 and gear 51, drives shaft 52, mounted in yoke 22. Shaft 52, through pinions 53, drives shaft 54 in movable arm 27. Shaft 54, through pinion 55 and gear 56, drives a vertical shaft 57, mounted in movable arm 27. Shaft 57, through pinions 58, drives a shaft 59, mounted in movable arm 26, and shaft 59, through pinion 60 and gear 61, drives shaft 36, thereby rotating the ironing plate 34, while the operator manipulates the ironing head over the pressing buck. 95

The pressing buck 62, contains electric heating elements 63, the energizing circuit for which is controlled by switch 64, on standard 21. The pressing buck is operated vertically 100 to and from the ironing head, being constructed with an extension 65 passing downwardly through the table 23. A foot lever 66, pivotally mounted on shaft 67, in standard 21, is provided with a shiftable fulcrum 105 member 68, in engagement with lever 69, which is pivotally connected with a movable arm 70, connected to extension 65. The arrangement allowing the buck to be raised on depressing lever 66.

Movable arm 70 is connected at the point 72, with lever 69. The pivotal point 72 to which the actuating power is applied, is therefore between the fulcrum point 73 and 5 the point 74, carrying the weight represented by the sliding extension 65 and buck 62. The foot lever 66 has a foot pedal 75. It may be noted that the fulcrum point 67 is between pedal 75, and member 68, mounted 10 on the short arm 76, of lever 66. On depressing pedal 75, the member 68 will be correspondingly raised, which, through lever 69, serves to raise the point 72, and therefore, to raise the buck 62.

15 Referring to Fig. 7, the switches 47 and 64, may be manipulated independently, to control the respective electric circuits for energizing the heating elements in the pressing-buck and in the ironing head, and the 20 switch 49 may be manipulated to control the electric motor for operating the same independently of the heating elements.

In use, the garment to be pressed is placed 25 upon or drawn over the pressing buck, or on such portion of it as may be best adapted for pressing the garment. The electric heaters are energized for heating the pressing buck and the ironing head. Upon the 30 garment being in position for pressing, the foot-lever is depressed, thereby raising the buck and garment into contact with the ironing head. The operator then closes the motor circuit through the switch 49, and, as the ironing plate rotates upon the garment, the operator grasps the handle 33, and 35 passes the ironing head over the garment until the same is smooth. Although the material to iron may be of varying thickness, this is automatically taken care of through 40 the yieldable pressure exerted by the operator upon the foot-lever. Exact counter-balancing of the parts is attained by manipulation of the fulcrum block. The padding on the pressing buck may be taken off and

replaced at will, and the parts may be counterbalanced accordingly. 45

I claim:

1. In a garment press, the combination with a standard and a table supported thereby, and pressing members carried 50 thereby and movable relative to one another, and one of said pressing members being disposed beneath the other, of a standard for the lowermost pressing member arranged to slide relatively through the table, a lever 55 pivotally connected to the pressing member standard, a foot lever pivotally mounted in the main standard, a fulcrum block adjustably secured to the foot lever and on the relatively shorter arm thereof, a link 60 lever having one extremity pivotally connected to the first-named lever and having the opposite extremity in engagement with the fulcrum block, and means for adjusting the fulcrum block to and from the fulcrum 65 point of the foot lever.

2. In a garment press, the combination with a standard and a table supported thereby, and pressing members above the table and movable relative to one another, one of 70 the pressing members being disposed beneath the other, of a standard for the lowermost pressing member slidable relatively through the table, a lever pivotally connected to the pressing member standard and 75 having its free end in contact with a fulcrum point on the main standard, a foot lever pivotally mounted in the main standard and having a longitudinally slotted short arm, a fulcrum block adjustably secured to said short arm in said slot, and a link lever having one extremity pivotally connected to the first-named lever and having its opposite extremity in engagement with the fulcrum block. 80

Signed this 6th day of June, 1922.

YOBIE NAKANISHI.
